(57) **CLAIM**

The ornamental design for a multi position stand, as shown and described.

DESCRIPTION

FIG. 1 is a front perspective view of a stand showing my new design;

FIG. 2 is a front view of the stand shown in FIG. 1;

FIG. 3 is a rear view of the stand shown in FIG. 1;

FIG. 4 is a left side view of the stand shown in FIG. 1;

FIG. 5 is a right side view of the stand shown in FIG. 1;

FIG. 6 is a top view of the stand shown in FIG. 1;

FIG. 7 is a bottom view of the stand shown in FIG. 1; and,

FIG. 8 is a front perspective view of the stand shown in FIG. 1 shown supporting a gaming device.

The broken line showing of a gaming device in FIG. 8 is meant to illustrate possible use and forms no part of the claimed design.

The broken line showing of the screw, attachment points and mechanisms and base shows unclaimed subject matter for the design in those drawings.
